UNITED STATES PATENT OFFICE

JOSEPH CUSSON, OF BAY CITY, MICHIGAN, ASSIGNOR TO JOHN KING AND SAMUEL CUSSON, OF SAME PLACE.

ATTACHMENT TO SALT-GRAINERS.

SPECIFICATION forming part of Letters Patent No. 321,345, dated June 30, 1885.

Application filed February 18, 1885. (No model.)

To all whom it may concern:

Be it known that I, JOSEPH CUSSON, of Bay City, in the county of Bay and State of Michigan, have invented new and useful Improvements in Salt-Grainers; and I do hereby declare that the following is a full, clear, and exact description thereof, reference being had to the accompanying drawings, which form a part of this specification.

10 This invention relates to certain new and useful improvements in attachments to salt-grainers; and the invention consists in so constructing and operating scrapers employed for the purpose of automatically scraping the salt 15 as deposited in the grainers, where such deposit is induced by the operation of circulating steam through the pipes running through said grainers and just above their bottoms, which will scrape the salt from underneath such steam- 20 pipes as well as from the more exposed portions of the grainer. There are various mechanical devices employed for scraping the salt from one end of the grainer to the other, and thence out upon an inclined way, which 25 scrape the exposed portions of the bottom, and also take the salt which may be deposited on the tops of the pipes, allowing, however, a ridge of salt to gradually accrete below said pipes, which accretion must be removed by 30 hand frequently, or the proper circulation of the brine through the grainer is obstructed and the salt generally damaged in color.

Figure 1 is a perspective view of a grainer, showing my improved attachment as connected with rotary scrapers. Fig. 2 is an enlarged elevation showing more clearly the construction of such attachment.

In the accompanying drawings, which form a part of this specification, A represents a salt-grainer which is provided with a system of steam-pipes, B, as in the usual construction of such devices, and having at one end an inclined table, C, which leads to the draining-board. At each side of the grainer, and at a suitable distance above the same, I secure the horizontal ways D, terminating at one end in inclined ways E, which are of the same pitch as that of the inclined table C. Journaled in proper bearings at this end of the grainer is a shaft, F, which carries near each end thereof a pulley, groove, or sprocket-wheel, G, around

which endless cables or chains H pass to and around a similar pair of wheels, I, upon the shaft K, journaled in boxes upon the upper ends of the standards J. In the drawings 55 these devices are shown as upon one side of the grainer; but it should be understood that the duplicate of them are upon the opposite side also, both working in unison and harmony.

Oare risers secured to the sides of the grainer at or near the foot of the inclined ways E. Journaled upon stub-shafts projecting inwardly from these risers are the grooved pulleys P, beneath which the rope or endless chain travels, the intention of these pulleys being merely to 65 compel the chains carrying the scrapers to travel in a horizontal plane along the length of the ways D.

Upon the top of the standards J and O I secure the inclined ways R. S is a cross-bar or 70 rod secured at its ends to the cables or chains H, and upon this rod the scraper T is pivotally secured. This scraper consists of a suitable number of triangular frames, a, pivotally secured at one of their corners upon the bar S, 75 and at one of the other corners there is secured the bar scraper-plate V by means of hangers b, pivotally secured to the shaft W; and the outer or lower edge of this scraper-plate is notched, so as to straddle the steam-pipes in 80 the bottom of the grainer, and upon each end of the rods S and W are secured the wheels X, adapted to travel upon the ways R and D.

Pivotally secured to the front, and near the upper edge of the scraper V, are the levers c 85 and d, the upper ends of the former being also pivotally secured to a bar, E', while the latter are in like manner secured to a bar, F', while the lower ends of these levers c d are pivotally secured to small scrapers h, which are thus alternately connected to the bars E' and F'. The latter are adapted to have a reciprocating motion, which, being given in opposite directions to each of the bars, forces the lower portion of these small scrapers h, which are notched 95 in their upper edge for that purpose, to project beneath the pipes B, and in their travel remove the salt from under such pipes. As the scraper V starts from the foot of the grainer opposite the inclined way C, the ends of these 100 bars E' F' are brought into contact with suitable buttons, i, which compel each of these

bars to move in opposite directions, and as the scrapers arrive near the end of the grainer, which terminates in the inclined way C, other stops, *k*, are arranged to reverse the position 5 of the bars E' F', thereby withdrawing the projecting portions of the small scrapers *h* from beneath the pipes.

In practice motion is communicated to the shaft F from any convenient power, causing 10 the chains to move slowly and drag the scraper through the grainers, producing an agitation of the brine, and gathering all the salt that has been precipitated from underneath the pipes as well as from the more exposed portions of 15 the bottom of such grainer. In the continued movement of the parts the scraper is compelled to travel up the inclined table, deposit the collected salt upon the draining-board, and thence the scraper passes on, following the 20 change of the direction in the run of the chains down the upper inclined ways. In this return movement the scraper-blade is projecting upwardly. In the further travel of the parts the frames *a* of the scraper strike the 25 fleeting portion *m* of the ways D, which causes the scraper to reverse its position, the wheels carrying the same following the curve of this portion of the ways, down which they slide or roll until they rest upon the horizontal portion 30 of such ways to resume their travel toward the inclined end of the grainers.

Although this improvement is shown as attached to a scraper actuated by a rotary motion, it will readily be seen that the same improvement may be attached to scrapers car- 35

ried by a reciprocating motion, and such I deem to be within the scope of my invention.

What I claim as my invention is—

1. In combination with a salt-grainer having a system of steam-pipes therein, and with 40 a scraper adapted to remove the salt from the bottom of such grainer, a series of scrapers adapted to be projected beneath the steam-pipes, and be withdrawn therefrom laterally, substantially as and for the purposes de- 45 scribed.

2. The combination, in a salt-grainer having steam-pipes, and with a scraper adapted to remove the salt from such grainer, a series of 50 small scrapers arranged in pairs, and adapted to be projected under the steam-pipes, and removed therefrom by the reciprocal action of two bars, one above the other, such reciproca- 55 tion being in opposite directions and connected with such small scrapers by the pivoted levers, substantially as and for the pur- poses specified.

3. The combination, with a salt-grainer having steam-pipes, of the notched scraper adapted to straddle the steam-pipes, with a series 60 of small scrapers pivotally secured to such main scraper and actuated by stops *i* and *k* through the bars E' F', and the levers connecting such bars with such small scrapers, substantially as and for the purposes set forth. 65

JOSEPH CUSSON.
